UNITED STATES PATENT OFFICE.

HENRY CHAPMAN PERDUE, OF HOBART, INDIANA.

GAS-PRODUCER.

991,082.

Specification of Letters Patent.

Patented May 2, 1911.

Application filed April 14, 1910. Serial No. 555,329.

To all whom it may concern:

Be it known that I, HENRY CHAPMAN PERDUE, a citizen of the United States, residing at Hobart, county of Lake, and State 5 of Indiana, have invented certain new and useful Improvements in Gas-Producers, of which the following is a specification.

My invention relates to improvements in gas generators and more particularly to 10 means for agitating the fuel being converted into gas.

The object of the invention is to provide an improved gas producer of simple construction and efficient in operation and provided with efficient means for agitating the fuel to prevent caking and the formation 15 of clinkers.

The invention consists in the combination and arrangement of parts hereinafter described and claimed.

The invention will be best understood by reference to the accompanying drawings forming a part of this specification, and in which—

25 Figure 1 is a vertical section of a gas producer embodying my invention, and Fig. 2, a horizontal section of the same.

The preferred form of construction as illustrated in the drawings comprises a 30 suitable gas generating chamber 1 mounted in a suitable water filled well or ash pan 2 through which the ashes of combustion may be removed in the usual manner. At either side chamber 1 is provided with water 35 filled casings 3 and 4 in which hollow shafts 5 are rotatably mounted. A supply chamber 6 is secured to the exterior side of casing 3 in open communication with the open ends of shafts 5 and a supply pipe 7 leads to 40 said chamber 6 and serves to supply air and steam thereto from a suitable source of supply.

Outside of casing 4 shafts 5 are provided with worm wheels 8 meshing with worm gears 9 carried by an operating shaft 45 10 adapted to be driven by means of pulleys 11. Shafts 5 carry radial perforated projections 12 adapted to act as agitating arms when said shafts are rotated. At the top chamber 1 is provided with a common form 50 of bell-hopper feed 13 for the introduction of fuel into said chamber and with a gas flue 14 for the withdrawal of gas therefrom.

In operation a fire is started and maintained in chamber 1 and fuel supplied to 55 said fire in the usual manner. Shaft 10 is operated to cause rotation of shafts 5 where-

by arms 12 are caused to constantly agitate the fuel in the chamber to prevent caking or the formation of clinkers and air and steam are introduced into said chamber through 60 supply chamber 6 and the perforations in arms 12.

It will be observed that shafts 5 rotate in the same direction so that the projections 12 on adjacent sides of adjacent shafts pass 65 each other moving in opposite directions thus effectively crushing any large cinders or clinkers. By this construction it will be observed that the burning fuel will be constantly agitated and broken up to prevent 70 the formation of clinkers and air and steam supplied thereto to support combustion and produce the gas. The gas produced is drawn off through flue 14 in any usual or desired manner.

While I have illustrated and described the preferred form of construction for carrying my invention into effect this is capable of variation or modification without departing from the spirit of the invention. 80 I therefore do not wish to be limited to the exact details set forth, but desire to avail myself of such variations and modifications as come within the scope of the appended claims.

Having described my invention what I claim as new and desire to secure by Letters Patent is:

1. The combination with a gas generating chamber, of a plurality of hollow agitating 90 members rotatably mounted in said chamber on substantially the same level and provided with short radial perforated projections; means for supplying air and steam to said members; and means for rotating said members in the same direction, substantially as described.

2. The combination with a gas generating chamber, of water cooled casings at opposite sides of said chamber; a plurality of hollow 100 and perforated agitating shafts rotatably mounted in said casings on substantially the same level; a supply chamber secured to one of said casings in open communication with the open ends of said shafts; means for 105 supplying air and steam to said supply chamber; and means for rotating said shafts in the same direction, substantially as described.

3. The combination with a gas generating 110 chamber, of water cooled casings at opposite sides of said chamber; a plurality of hollow

agitating shafts rotatably mounted in said casings on substantially the same level and provided with short radial perforated projections; a supply chamber secured to one of said casings in open communication with the open ends of said shafts; means for supplying air and steam to said supply chamber; worm wheels on said shafts; an operating shaft carrying worm gears meshing with

said wheels; and means for operating said operating shafts, substantially as described.

In testimony whereof I have signed my name to this specification in the presence of two subscribing witnesses.

HENRY CHAPMAN PERDUE.
